UNITED STATES PATENT OFFICE.

OTTO EICK, OF ST. LOUIS, MISSOURI.

DESIGN FOR A RUBBER HEEL.

60,326.

Specification for Design.

Patented Feb. 7, 1922.

Application filed August 25, 1921. Serial No. 495,401. Term of patent 7 years.

To all whom it may concern:

Be it known that I, Otto Eick, a citizen of the United States, residing at St. Louis, State of Missouri, have invented a new, original, and ornamental Design for Rubber Heels, of which the following is a specification, reference being had to the accompany-

ing drawing, forming part thereof, in which is shown a bottom view of the heel.

I claim.

The ornamental design for a rubber heel as shown.

OTTO EICK.
